UNITED STATES PATENT OFFICE.

CHARLES VERBSKY, OF CLEVELAND, OHIO.

TRUSS.

Application filed August 13, 1925. Serial No. 50,028.

This invention relates to improvements in trusses, the primary object being to construct a truss wherein the supporting pad will readily and automatically adapt itself to different positions as required due to the different postures assumed by the wearer.

A further object is to provide a truss wherein the supporting pad may be manually adjusted to different positions as required by the particular physical make-up of the holder.

Other objects will be apparent in the following descriptive matter.

In the accompanying drawings forming a part of this application,

Figure 1 is a front elevation of my improved truss;

Figure 2 is a plan view, the web waist band being eliminated;

Figure 3 is a sectional view incidentally illustrating approximately the angle at which the pad is normally set;

Figure 4 is a cross sectional view of the pad and its supporting bar and spring; and

Figure 5 is a vertical longitudinal section showing the connection between the supporting bar and leaf spring.

Similar characters of reference designate similar parts throughout the following specification and accompanying drawings.

The average truss is extremely uncomfortable to the wearer, it being adjustable to various positions only with unnecessary difficulty and is generally objectionable due to the fact that the supporting pads do not readily adapt themselves to different positions as required by movement of the body of the wearer. With my truss the pad is yieldable in all directions, may be adjusted vertically and horizontally and will automatically position itself to operate at maximum efficiency under all conditions.

The supporting elements comprise a substantially semi-circular waist band 6 one end 7 of which is attachable to the web portion 8 while its other end is rolled to provide a tubular support 9 for a pad. At the outer end of this tubular pad support 9 I fix a screw or the like device 10 which is removably attachable to a fastening device 11 having a key slot 12 therein, this fastening device being carried at the free end of an adjustable web band 8. In order to provide a necessary degree of stiffness in the semi-circular band 6, I curve the same transversely as indicated in Figure 1, this curvature being

decreased and vanishing toward the extremities of this band so as to allow a certain degree of resiliency near the ends.

A supporting arm or bar 13 has one end 14 extended at an obtuse angle to the main portion and rolled upon itself for connection to the tubular support 9. A screw or the like fastener 15 permits tightening of the rolled end 14 upon the tubular support 9 and as is obvious permits longitudinal and angular adjustment of the bar upon the support. This bar 13 is provided with a longitudinal slot 16 extending upwardly from a point near its lower end. A relatively long flat leaf spring 17 has one end 18 contacting with the lower inner face of the supporting bar 13 and is slidably adjustable on the bar as indicated in Figures 1 and 5. The connection between the spring and bar consists of a guide stud 19 or finger 19 which is carried by the spring and is slidable in the slot 16, and a set screw or the like fastener 20 which serves to lock the parts at any desired point.

This leaf spring 17 is bent away from the bar and then into parallel relation at its outer end 21, said end being substantially co-extensive with the rolled end 14 of the bar 13.

While other types of pads may be employed I preferably construct one of non-corrodible metal and shape the same substantially as shown in Figure 3. It will be noted that the shape closely resembles a spoon and is hollow so as to minimize the weight and space required. This pad 22 encloses a major portion of the leaf spring 17 and has its upper reduced end 23 riveted or otherwise secured to the upper free end 21 of said spring.

With a truss constructed as set forth the general location of the pad may be varied through loosening the set screw or bolt 15 and sliding the rolled end of the supporting bar 13 along the tubular support 9. It is also understood that the angle of the supporting bar 13 may be readily varied with respect to the tubular support 9. Vertical adjustment of the pad 22 is readily effected through loosening the set screw 20 and sliding the spring longitudinally of the supporting bar 13, the guide stud 19 serving to retain the elements in proper alignment. With the pad 22 positioned substantially as shown in Figure 3, there will be a lifting action upon the affected part of the body and regardless of various movements of the wearer, this pad will invariably adapt itself to the

different positions. The leaf spring 17 is of such a gauge as to provide a very high degree of resiliency and it is believed clear that the pad will automatically shift its position as conditions may require.

Certain minor changes in the details of construction may be resorted to, and such of these changes as may fall within the scope of the appended claim, I consider within the 10 spirit of my invention.

I claim:

A truss including, a main support, a relatively long supporting bar angularly ad-

justable on the main support and having a longitudinal slot, a leaf spring having its 15 ends substantially co-extensive with the ends of the bar, means engageable in the slot to effect slidable connection between corresponding ends of the bar and spring, said spring being bent away from and then substantially in parallel relation to the bar, and a spoon-like pad arranged in longitudinal alinement with the bar and having one end connected to the other end of said spring.

In testimony whereof, I affix my signature.

CHARLES VERBSKY.
